UNITED STATES PATENT OFFICE.

MASON D. COFFMAN, OF FLORENCE, ARIZONA.

CAN PERFORATOR AND COVER.

1,295,004.

Specification of Letters Patent. Patented Feb. 18, 1919.

Application filed September 12, 1918. Serial No. 253,777.

To all whom it may concern:

Be it known that I, MASON D. COFFMAN, a citizen of the United States, residing at Florence, in the county of Pinal and State 5 of Arizona, have invented certain new and useful Improvements in Can Perforators and Covers, of which the following is a specification.

This invention relates to a cover for cans 10 containing food stuffs and is more particularly adapted for use on condensed milk cans, evaporated cream cans, and similar cans, which merely require perforations in one end thereof for the purpose of dispensing 15 the contents thereof.

The primary object of the invention is to provide a removable cover which is adapted to fit over one end of the can and punch the 20 perforations so that either one may be used to pour the contents from the can, the device being adapted to be held in position so that the perforations will be closed when the can is not in use whereby the contents of the can will be protected.

25 A further object of the invention is to provide a device of this character which consists of comparatively few parts and is simple in construction but durable and well adapted to withstand the rough usage to 30 which devices of this character are ordinarily subjected.

For a full description of the invention and the advantages and merits thereof reference is to be had to the following description 35 and accompanying drawings, in which:

Figure 1 is a side elevation of the invention showing its manner of application to a can, the latter being illustrated by dotted 40 lines.

Fig. 2 is a transverse vertical section through the device.

Referring to the drawings, wherein is 45 illustrated the preferred form of my invention, in which like characters of reference indicate corresponding parts throughout the several views an annular band 1 is adapted to fit around the exterior of the can at one end thereof and is of comparatively short 50 length so that only a portion of one end of the can is embraced. Mounted on one end of this band is a cap 2 which consists of the top circular plate 3 having an annular flange 4 at its outer marginal edge, this annular 55 flange 4 being adapted to embrace one end of the annular band 1. At diametrically

opposite points, the flange 4 is provided with screw threaded openings into which is extended the screw threaded studs 5, carrying fingers 6 which have their terminals curved 60 inwardly toward the band 1 so that they may be received in depressions 8 formed at diametrically opposite points on the band 1.

The top plate 3 of the cap 2 is provided with punchers 9 each of which consists of a 65 spur 10 having a restricted neck portion 11 and a relatively short tapered shank 12 which is rigidly wedged into the plate 3 so that the puncher is held in the proper position. Each punch projects into the space 70 beneath the plate 3 at diametrically opposite points within the can when in position.

The restricted neck portion 11 is provided with a washer 13 which rests upon the top of the can when the spurs 9 have been forced 75 into the top thereof. The fingers 6 are for the purpose of retaining the cap 2 and the annular band 1 in their proper relative positions since it will be noted that the members 6 may be swung on the studs 5 to cause the 80 curved terminals to disengage the recesses 8 whereupon the cap may be removed from the annular band. In use, the device as illustrated in Fig. 2 will be placed upon the end of the can and forced partly downwardly until the punchers provide the perforations in the can at diametrically opposite points, this will facilitate removal of the contents since one hole will serve to pour the milk while the other will permit the air to 90 enter the can to permit the flow to be continuous. When the can is to be set aside or packed away for future use, the cap will be replaced and the fastening elements will be 95 swung on the stud 5 until the ends thereof engage the recesses 8 whereupon the cap will be held sufficiently snug to prevent casual or accidental displacement and since the washers on the restricted portions of the punchers will surround the perforations in 100 the end of the can it will be obvious that no leakage will occur and the contents of the can will be thoroughly protected.

The foregoing description and accompanying drawings have reference to what 105 might be considered to be the preferred or approved form of my invention. I desire it to be understood that I may make such changes in the construction combination and arrangement of parts, materials dimensions 110 et cetera, as may prove expedient and fall within the scope of the appended claims.

Having thus fully described my invention what I claim as new and desire to secure by Letters Patent, is:—

1. A device of the character described comprising a removable annular band having a cap mounted thereon and removable with the band, punchers carried by the cap and means carried by the cap and engageable with the band to releasably hold the cap in engagement with the said band.
2. A device of the character described comprising a cap having depending spurs provided at diametrically opposite points, an annular band, and rotatable fastening devices carried by the cap and adapted to engage and disengage the said band to releasably hold the said cap in position on the band.
3. A device of the character described comprising an annular band provided at diametrically opposite points with recesses, a cap mounted on one end of the band and

provided with spurs depending into the space embraced by the said band, and fastening devices carried by the cap and adapted for reception in the said recesses to maintain the said cap in position on the end of the band for preventing displacement of the said punchers.

4. A cover adapted for mounting on the end of a can, comprising an annular band adapted to embrace one end of the can, a cap removably mounted on the end of the band and provided with spurs adapted to perforate one end of the can, and fastening devices carried by the cap and adapted to engage the annular band to maintain the said cap in position on one end of the can.

In testimony whereof I affix my signature in presence of two witnesses.

MASON D. COFFMAN.
